UNITED STATES PATENT OFFICE.

GUSTAVE SHENKEL, OF BROOKLYN, NEW YORK.

DESIGN FOR A WALL BRACKET.

Application filed July 20, 1925. Serial No. 14,143. Term of patent 7 years.

To all whom it may concern:

Be it known that I, GUSTAVE SHENKEL, a citizen of the United States, residing in the city of New York, borough of Brooklyn, county of Kings, State of New York, have invented a new, original, and ornamental Design for Wall Bracket, of which the following is a specification, reference being had to the accompanying drawings, forming a part hereof, in which—

Figure 1 shows an elevation of a wall bracket illustrating my new design.

Figure 2 is a cross sectional view on line 2—2 of Figure 1.

I claim:

The ornamental design for a wall bracket, as shown.

GUSTAVE SHENKEL.
